PICKING MECHANISM FOR LOOMS

Howard M. Van Alstyne and Walter Bell, Rensselaer, N. Y., assignors to F. C. Huyck & Sons, Rensselaer, N. Y., a corporation of New York

Application March 1, 1949, Serial No. 78,928

5 Claims. (Cl. 139—142)

1

Our invention relates to improvements in picking mechanisms for looms and particularly to improvements in mechanisms of the general type disclosed in our U. S. Letters Patent No. 1,966,704, dated July 17, 1934.

The aforesaid Letters Patent discloses a device which is actuated by the energy in a rotating fly wheel for pulling the picker straps which are attached to the picker sticks, and the operation of which is controlled, in part, by a reciprocating sleeve moving in synchronism with the lay of the loom, and, in part, by a timing device actuated by the pattern mechanism of the loom. Whether the reciprocating sleeve effects or does not effect an operation of the picking mechanism is controlled by said timing device.

One of the objects of our invention is to provide a picking mechanism of the general type disclosed in our Letters Patent aforesaid in which the various elements are of an improved design, cooperate in a different manner, and may be easily adjusted to function in smooth, precisely timed relation to each other with a minimum of shock and wear.

Another object is to provide a picking mechanism which may be so adjusted that there is substantially no lost motion between the various elements, with the result that shock, which otherwise would occur due to the taking up of this motion when the mechanism is actuated, is eliminated.

Another object is to provide an improved means for actuating the picking mechanism and an improved means cooperating therewith for controlling the timing thereof.

Another object is to provide an improved, readily accessible means for precisely adjusting the interval during which the clutch elements are held in engagement.

A further object is to provide a picking mechanism having an improved cam and cam follower combination or assembly in which the followers, except during the actual picking motion, are stationary.

We accomplish these objects by means of the novel elements and the combinations and arrangements thereof described below and illustrated in the accompanying drawing in which—

Fig. 1 is a plan view of our device;

Fig. 2 is a vertical section thereof with portions broken away;

Fig. 3 is a section of Fig. 1 in the plane 3—3;

Fig. 4 is a side elevation view of our device;

Fig. 5 is a side elevation view of two of our de-

2

vices, one of which is disposed at each end of the loom;

Fig. 6 is a section of Fig. 1 in the broken plane 6—6 but with the timing control mechanism in the non-picking position.

Fig. 7 is a fragmentary plan view with portions broken away showing a modification of our device;

Fig. 8 is a section of Fig. 7 in the plane 8—8; and

Fig. 9 is an enlarged section in the plane 8—8 of Fig. 7 showing more clearly a detail also shown in Fig. 8.

Referring to the drawings—

15 Our device comprises a stationary, horizontal shaft 1 which is rigidly secured in the uprights 2 on the base 3 by means of the bearing-like caps 4 and cap screws 5.

Rotatably mounted on bearings 6 on the shaft

20 1 is a comparatively heavy fly wheel 7 which, as illustrated, has a V-shaped, circumferentially-extending groove 8 therein adapted to receive the belt 9 driven by the motor 10 (see Fig. 5). The inner surface 11 of the rim of the fly wheel is

25 frusto-conical and forms the female driving element of a clutch. Both slidably and rotatably mounted on the shaft 1 is the male, frusto-conical, driven element 12 of the clutch having circumferentially-spaced recesses in the frusto-conical surface thereof in which are secured friction blocks 13. On the side opposite the fly wheel,

30 the element 12 is provided with a comparatively large hub 14, the radius of curvature of the peripheral surface 15 of which increases uniformly from the top thereof when the parts are in the non-picking position, shown in Fig. 3, to the bottom. Secured to the top of the hub 14, when in this position, is the picker strap 16 which is adapted to be wound partially around the surface 15 of the hub when the clutch element 12 is

35 rotated in the direction of the arrow, shown in Fig. 3; the increasing radius of curvature of the surface 15 accelerating the rate of winding. Surrounding the shaft 1 and between the clutch elements 7 and 12 is the helical, compression spring

40 17 which normally holds these elements out of cooperative relation. The distance which the element 12 may move away from the element 7 is adjustably limited by means of the collar 18 which is threaded on the shaft 1 and secured in adjusted position by means of the set screw 19. Only a very slight axial movement of the element 12 is necessary in order to move it into or out of engagement with the driving element 7.

45 Surrounding the shaft 1, in spaced relation

thereto and adjustably secured to the end of the hub 14 on the element 12 by means of a plate 20 and cap screws 21, is a cam 22 having two, circumferentially-spaced, arcuate, raised surfaces 23 and 24 which are coplanar and normal to the axis of the shaft 1.

Slidably but non-rotatably mounted on the shaft 1 is a sleeve 25 having oppositely-disposed arms 26 and 27 thereon extending towards the cam 22; and rotatably mounted in the ends of these arms, are the follower rollers 28 and 29 adapted to cooperate with the cam 22. Pivots mounted at 30 on the sleeve 25 are two oppositely-disposed links 32 and 33 which are connected together by the upwardly-extending, clevis-like element 31 to form a timing element which controls the operation of the picking mechanism. The right hand ends of the links 32 and 33, as viewed in Figs. 1, 2 and 4, are semicylindrical, for a reason which will be explained below, and the left hand ends of the links are also illustrated as semicylindrical and coaxial with the pivotal mounting 30. The axis of the semicylindrical portions at the right hand ends of the links and the axis of the pivotal mounting 30 are parallel and, when the timing element is in picking position are coplanar with the axis of the shaft 1. The links 32 and 33 and the element 31 can rotate freely in a counter-clockwise direction, as viewed in Figs. 2 and 4, but rotation in a clockwise direction beyond the position shown in Figs. 1, 2 and 4 is prevented by the bottoms 36 of the recessed portions 37 in the sleeve 25.

Our preferred mechanism for swinging the links 32 and 33 upwardly, or in a counter-clockwise direction about their pivotal mounting 30, is illustrated in Figs. 7 and 8, as is also our preferred means forming an adjustable stop for limiting the movement of the sleeve 43. However, we have illustrated in Figs. 1, 2, 4, 5 and 6 a modification thereof in which a horizontal shaft 37 parallel to the shaft 1 is mounted in a bearing on top of the sleeve member 25. Secured to one end of the shaft is the upright arm 38 which is adapted to be connected, by means of a rod 38' (see Fig. 5), to the pattern mechanism of the loom or to means controlled by the pattern mechanism of the loom for rocking the shaft 37' in its bearing. The shaft 37' extends between the branches of the clevis-like element 31, as best shown in Fig. 2 and, between the branches is provided with a laterally-extending projection 39 which, when the arm 38 is moved to the position shown in Fig. 6, is adapted to cooperate with and swing the element 31 and the links 32 and 33 in a counter-clockwise direction about the axis of the mounting 30, as shown in Fig. 6 and in dotted outline at 32' in Fig. 4. A helical spring 40, lighter than spring 17, surrounding the shaft 1 is compressed between the collar 18 and the sleeve 25 and normally holds the sleeve 25 against the adjustable collar 41 which is secured to the shaft 1 by means of a set screw 42.

Slidably mounted on the shaft 1 is a second sleeve 43 which is normally held against the adjustable collar 44, secured to the shaft 1 by the set screw 45, by means of the helical spring 46 which is compressed between the sleeve 43 and the adjustable collar 47 which is threaded on the shaft 1 and secured in adjusted position by means of the set screw 48.

Pivots mounted on the sleeve 43 at 49, is the lever or bell crank 50; the axis of the pivotal

mounting being horizontal and coplanar with the axis of the shaft 1. The lower portion of the bell crank 50 is bifurcated and straddles the sleeve 43 so that there are arms 51 and 52 thereof on each side of the shaft 1. Rollers 53 and 54 are pivotally mounted in the extremities of the arms 51 and 52, respectively, and are adapted to cooperate with the adjacent semicylindrical ends of the links 32 and 33, as shown in the drawings. The bell crank 50 is adapted to oscillate about its pivotal mounting 49 on the sleeve 43 and this oscillating movement is effected by the eccentric mechanism, represented generally by the numeral 55 in Figs. 1, 2 and 4, which is driven from the main shaft 56 of the loom in synchronism with the lay of the loom (not shown). The length of the eccentric rod 57, which is pivotally connected to the bell crank 50 at 58 may be adjusted by means of the nut 59. Thus, as the bell crank 50 is oscillated by the eccentric mechanism, the common axis of the rollers 53 and 54 may oscillate in a cylindrical surface indicated by the dot and dash line 60 in Figs. 2 and 4, so that, at times, the common axis of the rollers 53 and 54 is below the axis of the shaft 1, and at other times, above the axis of the shaft 1.

When in operation, it is to be understood that the bell crank 50 is being constantly oscillated in synchronism with the oscillating movements of the lay of the loom. When the links 32 and 33 are in the position shown in solid lines in Fig. 4, which is the picking position, the downward movement of the rollers 43 and 54 brings them into rolling contact with the semicylindrical ends of said links. This contact of the rollers with the semicylindrical ends of the links 32 and 33 forces the sleeve 25 to the left against the compression of spring 40, and the rollers 28 and 29 which lie against, or substantially against, the raised surfaces 23 and 24 of the cam move the driven clutch element 12 against the compression of spring 17 into frictional engagement with the driving clutch element 7. When the normally non-rotating, driven element engages the rotating driving clutch element it is immediately picked up thereby and rotated in the direction of the arrow, shown in Fig. 3, and the picker strap 16 is wrapped around the surface 15 of the hub 14 to impart a quick and rapidly but smoothly accelerated movement to the picker stick 64 to which it is attached at 65 (see Fig. 5).

The rollers 28 and 29 continue to bear against the flat raised surfaces 23 and 24 of the cam, and hold the clutch elements in engagement, until they drop abruptly into the spaces 61 and 62 between said surfaces as said cam is rotated with the driven clutch element. The timing of the drop can be precisely adjusted by loosening the cap screws 21, rotating the cam, and tightening said screws to hold the cam in adjusted position. When the rollers drop off the raised surfaces of the cam the clutch elements are immediately disengaged by the spring 17, and the driven element is rotated back to its non-picking position by the pull exerted on the picker strap by the tension spring 63 attached to the picker stick on the opposite side of its pivotal mounting 68 from the point of attachment of said strap. The return movement of the driven element is limited by the stop 66.

As illustrated in the drawings, the rollers 53 and 54 are on dead center with the semicylindrical ends of the links 32 and 33 and the driven clutch element is then in full engagement with the driving clutch element. However, as the rollers 53

and 54 continue to move downwardly beyond this dead center position, they cease to hold the sleeve 25 and rollers 28 and 29 in advanced position against the compression of spring 40 and this spring forces the links 32 and 33 to swing upwardly or counter-clockwise about their pivotal mounting on the sleeve 25 and slip over the rollers 53 and 54 which instantly allows the rollers 28 and 29 to be retracted by spring 40 from the spaces between the raised portions of the cam, and the driven element to return to its non-picking position without interference.

Ordinarily, only a few thousandths of an inch spacing between the cooperating surfaces of the driving and driven clutch element is all that is necessary in order to maintain them separated, and hence, only a very slight axial movement of the driven member is necessary to bring it into frictional engagement with the driving member. Thus, by adjusting the positions of the various collars and the cam on the driven element, it is possible to regulate precisely the intervals during which the clutch elements are engaged and the rollers 53 and 54 are in contact with the links.

The oscillating bell crank 50 effects an actuation of the picking mechanism only when the rollers 53 and 54 move downwardly. On the upward movement thereof, the rollers simply lift the links out of their path and allow them to drop back into the picking position unless they are held in the non-picking position by the projection 39 on shaft 37.

The pressure with which the clutch elements are forced into or held in engagement may be varied by adjusting the collar 47 which controls the compression of spring 46. This spring makes the contact between the rollers 53 and 54, and the links 32 and 33, a yielding one and controls the pressure of the rollers on said links.

In Figs. 7, 8 and 9, we have illustrated, as mentioned above, our preferred timing mechanism and the mechanism which cooperates directly therewith to move the driven element of the clutch into engagement with the driving element. Those parts shown in these figures which are, or may be, identical with like parts in Figs. 1 to 6, inclusive, are indicated by the same reference numerals.

The principal differences between the device, as shown in Figs. 1 and 2, and the device, as shown in Figs. 7, 8 and 9, reside in some of the parts which are disposed to the right of the cam attached to the driven clutch element. Thus, the shaft 37' and the arm 38, best shown in Figs. 2 and 6, have been eliminated and a comparatively heavy block 69 having spaced uprights 70 thereon is welded to the clevis-like element 31 and serves normally, by its weight, to hold the links 32 and 33, which are pivoted at 30 to the sleeve 25, in the down position shown in Figs. 7 and 8. A horizontal bar 71 is carried between the uprights 70, and secured thereto is a flexible strap 72 (see Fig. 8) which extends partially around and is secured at its other end to the pulley 73 eccentrically mounted on shaft 74. The shaft 74 extends from end to end of the loom and is oscillated by the pattern mechanism of the loom (not shown). When oscillated in the direction of the arrow shown thereon, the links 32 and 33, are quickly pulled upwardly into the non-picking position and, when oscillated in the opposite direction, the links 32 and 33 are pulled downwardly into the picking position by gravity acting on the weight 69 and other parts pivoted at 30 to the sleeve 25. It is to be understood that there is similar mech-

anism at the other end of the loom for timing the movements of the picker stick at that end; and, of course, when the parts at one end of the loom are in picking position, as shown in Figs. 7 and 8, the parts at the other end of the loom are in the non-picking position.

The sliding movement of the sleeve 25 to the right, as viewed in Figs. 7 and 8, is limited by the threaded sleeve 75 (see also Fig. 9) which is positively fixed to the shaft 1 by the taper pin 76. Threaded on the sleeve 75 is a collar 76' which cooperates with the sleeve 43, slidably mounted on shaft 1, to form an adjustable stop limiting the movement of sleeve 43, and its attached parts, to the left; the collar 76' being positively held in adjusted position by set screw 77.

Pivoted at 78 to the collar 43 are the rocker arms or levers 79 and 80 which are secured together by means of the inverted U-shaped member 81 and which perform the same function as the bell crank 50. At their left hand ends, the arms 79 and 80 are bifurcated to receive the rollers 53 and 54, respectively, which are mounted on the pins 82 and 83, respectively. At their other ends, the arms 79 and 80 are provided with outwardly-extending, coaxial studs 84 and 85, respectively, on which the clevis-like element 86 is pivotally mounted. Adjustably secured to the cross member 87 of the element 86 is the upwardly-extending eccentric rod 88 which is understood to perform the same function as the eccentric rod 57, shown in Fig. 2, and to be connected to an eccentric mechanism, similar to that shown at 55 in Fig. 2, on the main shaft of the loom so that it is reciprocated in synchronism with the lay of the loom. The only difference being that, when the rod 88 moves downwardly, or away from the shaft on which the eccentric is mounted, the rollers 53 and 54 are swung upwardly; whereas, when the rod 57 moves to the left, or away from the shaft on which the eccentric is mounted, the rollers 53 and 54 are swung downwardly.

While we have described our invention in its preferred embodiment, it is to be understood that the words which we have used are words of description rather than of limitation and that changes, within the purview of the appended claims, may be made without departing from the true scope and spirit of our invention in its broader aspects.

What we claim is:

1. In a picking mechanism for a loom, the combination with a driving clutch element; of a driven clutch element; a picker strap actuated by said driven element; a spring normally maintaining said elements out of cooperating engagement; a cam on said driven element; a normally stationary follower cooperating with said cam for moving said driven element into cooperation with said driving element; a pivotally mounted lever adapted to be rocked about its pivotal mounting in synchronism with the lay of said loom and having a roller rotatably mounted on one arm thereof; a link and a pivotal mounting therefor operatively connecting said link to said follower and positioned to adapt one end of said link to swing into and out of the path of movement of said roller; and means adapted to be controlled by the pattern mechanism of said loom for controlling the movement of said link.

2. A picking mechanism for a loom comprising a stationary shaft; a first, comparatively heavy, clutch element rotatably mounted on said shaft, a motor for driving said element; a second clutch

element rotatably and slidably mounted on said shaft and adapted to slide into frictional engagement with said first element to be driven thereby; a picker strap actuated by said second element; a cam on said second element having two, circumferentially-spaced, flat, coplanar surfaces thereon; a first sleeve slidably but non-rotatably mounted on said shaft; a pair of rollers rotatably mounted on said sleeve and positioned to cooperate with the flat surfaces of said cam for moving said second element into engagement with said first element; a first spring cooperating with said second element and normally holding it out of engagement with said first element; a second spring cooperating with said sleeve and biased to urge said rollers away from said cam; means for adjustably limiting the movement of said second element away from said first element and the movement of said rollers away from said cam; a lever; means pivotally mounting said lever on said shaft with the end of one arm thereof adjacent said sleeve; means for oscillating said lever in synchronism with the lay of said loom; a link pivotally mounted on said sleeve adapted to swing into positive cooperative relation with said arm for sliding said sleeve axially of said shaft and effecting an engagement of said clutch elements when said arm moves in one direction only; and means adapted to be actuated by the pattern mechanism of said loom for swinging and holding said link out of cooperation with said arm.

3. In a loom picking mechanism of the character described having a shaft, a driving clutch element rotatably mounted thereon, a driven clutch element both slidably and rotatably mounted on said shaft and having a picker strap attached thereto, and a spring cooperating with said driven element and biased normally to hold it out of operative engagement with said driving element; the combination with means slidable on said shaft and cooperating with said driven element for sliding it into engagement with said driving element, of mechanism for actuating said slidable means comprising a lever, a pivotal mounting for said lever on said shaft adapting said lever to oscillate through a zone extending each side of the axis of said shaft; mechanism for oscillating said lever continuously, when said loom is in operation, in timed relation with the lay of said loom; a link cooperating with said slidable means; a pivotal mounting therefor adapting said link to swing into and out of a position in the path of movement of said lever; means for positively holding said link in said path when said lever is moving in one direction only to effect an actuation of said slidable means; and means adapted to be controlled by the pattern mechanism of said loom for controlling the position of said link.

4. In a loom picking mechanism of the character described comprising a shaft, a driving clutch element rotatably mounted on said shaft,

a driven clutch element rotatably and slidably mounted on said shaft to move into and out of engagement with said driving element, a picker strap actuated by said driven element, a spring cooperating with said driven element and normally maintaining it out of engagement with said driving element; the combination with mechanism slidably mounted on said shaft and cooperating with said driven element for moving it into engagement with said driving element, of means for actuating said slidably mounted mechanism comprising a lever, a mounting therefor on said shaft providing both a sliding movement of said lever axially of said shaft and a rocking movement thereof about an axis at right angles to the axis of said shaft, means adapted to rock said lever in timed relation to the movements of the lay of the loom, means on said mechanism, including a mounting therefor adapting said means to move into a position to cooperate with said lever for effecting an actuation of said mechanism by the movement of said lever, and into a position out of cooperation with said lever to prevent actuation of said mechanism thereby; and means cooperating with said last mentioned means for controlling the movements thereof.

5. In a loom picking mechanism of the character described comprising a shaft, a driving clutch element rotatably mounted on said shaft, a driven clutch element rotatably and slidably mounted on said shaft to move into and out of engagement with said driving element, a picker strap actuated by said driven element, a spring cooperating with said driven element and normally maintaining it out of engagement with said driving element; the combination with mechanism slidably mounted on said shaft and cooperating with said driven element for moving it into engagement with said driving element, of means for actuating said slidably mounted mechanism comprising a lever, a mounting therefor on said shaft providing both a sliding movement of said lever axially of said shaft and a rocking movement thereof about an axis at right angles to the axis of said shaft, means adapted to rock said lever in timed relation to the movements of the lay of the loom, means on said mechanism, including a mounting therefor adapting said means to move into a position to cooperate with said lever for effecting an actuation of said mechanism by said lever when said lever moves in one direction, and into a position out of cooperation with said lever to prevent actuation of said mechanism thereby; and means cooperating with said last mentioned means for holding the latter in a position out of cooperation with said lever.

HOWARD M. VAN ALSTYNE.
WALTER BELL.
